UNITED STATES PATENT OFFICE.

JOHN E. HUGON, OF RICHMOND, INDIANA.

GOVERNOR

SPECIFICATION forming part of Letters Patent No. 356,644, dated January 25, 1887.

Application filed April 14, 1886. Serial No. 198,822. (No model.)

To all whom it may concern:

Be it known that I, JOHN E. HUGON, of the city of Richmond, county of Wayne, and State of Indiana, have invented certain new and useful Improvements in Governors for Steam-Engines, of which the following is a specification.

My said invention relates to that class of steam-governors in which the governor-balls are connected directly to the governor-rod by straps or springs secured to said rod and said balls, as will be hereinafter more particularly described and claimed.

Referring to the accompanying drawings, which are made a part hereof, and on which similar letters of reference indicate similar parts, Figure 1 is a side elevation of a governor and its connections embodying my said invention; Fig. 2, a central vertical section of the same; Fig. 3, a view similar to a portion of Fig. 2, with the governor-balls extended; and Fig. 4, a top or plan view of Fig. 1.

In said drawings the portions marked A represent the governor-frame, in which are bearings for the various operating parts; B, the governor-rod, through which the governor operates on the valve, and which also revolves with the governor; C, the revolving hollow shaft surrounding said rod and carrying the governor-balls; D, said governor-balls, and E the straps or springs connecting the rod B and the governor-balls.

The frame A is secured to the shell of the valve, as shown, in the ordinary manner, and contains bearings for the driving-shaft A' of the governor and the hollow shaft C. It also carries a bell-crank lever, A², to which a rod, a², is connected, and by the spring a³ on said rod a² the valve-connection B' is held in contact with the rod B. The rod B passes up through the hollow shaft C, and its upper end or head, b, is connected by means of the straps or springs E to the governor-balls. Its lower end rests upon the connection B', which connects directly with and operates the valve. Being connected to the governor-balls, this rod, of course, revolves therewith.

The hollow shaft C is mounted in a vertical bearing in the frame A, as shown. It carries a bevel gear-wheel, e, upon its lower end, which engages with a similar bevel gear-wheel,

a', on the shaft A', and a yoke, C', upon its upper end, in which the governor-balls are pivoted. This shaft is provided with collars at both ends of its bearing in the frame A, 55 (which consist, preferably, as shown, of the yoke and the bevel gear-wheel, or are formed integrally therewith,) and therefore does not move vertically, but is only revolute.

The governor-balls D are substantially the 60 usual spherical governor-balls, the stems of which are bell-crank levers, as shown, (see, particularly, Figs. 2 and 3,) and are pivoted at the points of these bell-crank levers by pivots d to the yoke C'. The inner ends of 65 the arms of these bell-crank levers are preferably finished as arcs of circles struck from the centers of the pivots, as shown.

The straps or connections E are thin steel 70 springs, and are connected at one end to the head b of the rod B, and at the other ends directly to the balls D by screws e e', as shown, or otherwise. These springs rest against the 75 arc-shaped ends of the bell-crank levers, (thereby maintaining the same position laterally without reference to the position of the balls,) and thus pull in the same direction on the rod B at all times.

As will be observed, in my governor the yoke carrying the governor-balls is not subject to any vertical movement, but revolves always in the same plane, the operation upon the valve being entirely through the rod B and connections B'.

The operation of my said invention is as follows: When the speed of the engine tends to swing the governor-balls D out, the straps or springs E, because of their flexibility, permit them to do so, and at the same time, their length remaining the same, the springs, and 85 with them the rod B, are drawn down to close the valve. When the speed of the engine decreases, the governor-balls D will fall, which operation is aided by the retractile power of the springs, and the rod B is thereby and by 90 the operation of the bell-crank lever A², its rod a², and the spring a³ thereon caused to rise, as is also the connection B', and the valve is thus opened.

I am aware that springs or straps have been 100 employed as a means of connection between a rod or shaft having no vertical movement and

devices to which governor-balls were connected, whereby as said governor-balls were forced outwardly by centrifugal force the head carrying said devices and governor-balls would 5 be moved longitudinally on said shaft; but I am not aware that pivoted governor-balls secured to a yoke not longitudinally movable and connected to a vertically-movable rod have ever been produced, and I believe the 10 construction herein described and claimed to be new.

Having thus fully described my said invention, what I claim as new, and desire to secure by Letters Patent, is—

15 1. The combination, in a governor, of the governor-frame having bearings for the driving-shaft, and a hollow vertical shaft, said hollow vertical shaft being secured from longitudinal movement in its bearings and carrying a 20 yoke to which the governor-balls are pivoted, said governor-balls having bell-crank-shaped arms and pivoted to said yoke, a vertically-moving valve-rod passing through said hollow shaft, and springs secured to a head on 25 said rod and to said governor-balls, and bearing against the inner ends of the bell-crank-shaped arms of said balls, substantially as set forth.

2. The combination, in a steam-engine governor, of the frame-work, a hollow vertical shaft mounted and secured against longitudi- 30

nal movement in said frame-work, a yoke on said shaft, governor-balls pivoted to said yoke, a vertically-moving rod passing through said hollow shaft and connected to the valve, and 35 springs connecting the upper end of said rod to said governor-balls, said several parts being arranged and operating substantially as set forth.

3. The combination of the frame A, the rod 40 B, the hollow shaft C, having a yoke on its upper end, the governor-balls pivoted to said yoke, connections between said governor-balls and said rod B, a bell-crank lever, A', pivoted in the frame-work, and a spring, a', operating on 45 said bell-crank lever, the valve, and a driving-shaft, a, substantially as shown and described.

4. The combination, in a governor, of a vertically-movable rod connected with the valve, governor-balls pivoted to a revolving head or 50 yoke, and provided with bell-crank-shaped arms, and springs connected to said balls at their ends, and resting against the inner ends of said bell-crank-shaped arms in the center.

In witness whereof I have hereunto set my 55 hand and seal at Richmond, Indiana, this 30th day of March, A. D. 1886.

JOHN E. HUGON. [L. S.]

In presence of—

DAVID M. RICHEY,
FREDERICK W. HUGON.

Correction in Letters Patent No. 356,644.

It is hereby certified that the name of the patentee in Letters Patent No. 356,644, granted January 25, 1887, for an improvement in "Governors," was erroneously written and printed "John E. Hugon," whereas said name should have been written and printed *John E. Hugou*; and that said Letters Patent should be read with this correction therein that the same may conform to the record of the case in the Patent Office.

Signed, countersigned, and sealed this 8th day of February, A. D. 1887.

[SEAL.]

D. L. HAWKINS,
Acting Secretary of the Interior.

Countersigned:

R. B. VANCE,
Acting Commissioner of Patents.
